US00D971823S

(12) **United States Design Patent** (10) Patent No.: **US D971,823 S**
Chen (45) Date of Patent: ** Dec. 6, 2022

(54) **RECHARGEABLE BATTERY**

(71) Applicant: **Huiyu Chen**, Guangdong (CN)
(72) Inventor: **Huiyu Chen**, Guangdong (CN)
(**) Term: **15 Years**
(21) Appl. No.: **29/772,422**
(22) Filed: **Mar. 1, 2021**
(51) LOC (13) Cl. **13-02**
(52) U.S. Cl.
USPC **D13/103**
(58) **Field of Classification Search**

(57) **CLAIM**

The ornamental design for a rechargeable battery, as shown.

DESCRIPTION

FIG. 1 is a front elevational view of a rechargeable battery showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a perspective view thereof; and,

FIG. 8 is another perspective view thereof.
